(57) **CLAIM**

The ornamental design for a remote control for personal tracking, as shown and described.

DESCRIPTION

FIG. 1 is a perspective view of the invention.

FIG. 2 is a front plan view of the invention.

FIG. 3 is a top plan view of the invention.

FIG. 4 is a right elevational view of the invention.

FIG. 5 is a left elevational view of the invention.

FIG. 6 is a top view of the invention.

FIG. 7 is a front perspective view of the invention; and,

FIG. 8 is a side view of the invention.

FIGS. 1-8 show features of an article of footwear in phantom lines. The phantom lines are for illustrative purposes only, forming no part of the claimed design.
